CLAIM

The ornamental design for a combined opener and spout for an oil can, as shown, and described.

DESCRIPTION

FIG. 1 is a top plan view of a combined opener and spout for an oil can showing my new design;

FIG. 2 is a right side elevational view thereof, the left side being a mirror image of the right side shown;

FIG. 3 is a bottom plan view thereof;

FIG. 4 is a front elevational view thereof;

FIG. 5 is a rear elevational view thereof; and

FIG. 6 is a cross sectional view taken on line 6—6 of FIG. 2.

FIG. 1
